United States Patent Office

Des. 185,774
Patented July 28, 1959

185,774

COMBINED TRAY AND REMOVABLE BOWL

Robert A. Passolt, St. Paul, Minn., assignor to Brown & Bigelow, St. Paul, Minn.

Application August 14, 1957, Serial No. 47,362

Term of patent 7 years

(Cl. D44—10)

FIG. 2

FIG. 3

FIG. 4

Fig. 1 is an exploded plan view of a combined tray and removable bowl showing my new design;

Fig. 2 is a perspective view thereof;

Fig. 3 is an elevational view thereof; and

Fig. 4 is an elevational view with the device inverted from its position in Fig. 3.

I claim:

The ornamental design for a combined tray and removable bowl, as shown.
